UNITED STATES PATENT OFFICE.

SARA P. WILLIAMSON, OF CHICAGO, ILLINOIS.

SPOOL-HOLDER.

966,877.

Specification of Letters Patent.

Patented Aug. 9, 1910.

Application filed October 28, 1909. Serial No. 525,030.

To all whom it may concern:

Be it known that I, SARA P. WILLIAMSON, a citizen of the United States, residing at Chicago, county of Cook, and State of Illinois, have invented certain new and useful Improvements in Spool-Holders, of which the following is a specification.

My invention relates to sewing accessories and more specifically to improvements in 10 thread-spool racks or holders.

The object of my invention is the provision of a spool holder as mentioned which will be adapted to accommodate or hold a plurality of spools of thread of different 15 sizes in such a manner that the thread carried thereon may be readily uncoiled therefrom.

Another object is the provision of a spool rack so designed that the spools may be 20 readily and quickly arranged therein or removed therefrom; and further a device which will be simple of construction and hence of low cost to manufacture.

Other objects will appear hereinafter.

With these objects in view my invention 25 consists in a spool holder characterized as above mentioned and in certain details of construction and arrangement of parts all as will be hereinafter fully described and 30 particularly pointed out in the appended claim.

My invention will be more readily understood by reference to the accompanying drawings forming a part of this specification, and in which,

Figure 1 is a perspective view of my device in its preferred form, a spool in dotted lines being shown arranged therein, and Fig. 2 is a detail perspective.

Referring now to the drawings, 1 indicates 40 an elongate, preferably substantially rectangular base member of suitable dimensions. Centrally arranged upon and upwardly projecting from the upper surface 45 of the member 1, is a plurality of spaced bearing pins or studs 2 formed preferably integral with said base member, said pins being of such thickness as to adapt the same to be loosely received in the central longitudinally extending perforation usually provided in an ordinary thread-spool. Said pins as seen are of graduated length in order 50 to adapt the same to accommodate spools of various sizes. Rigidly secured by screws 3

to the respective extremities of the member 55 1 are upwardly projecting standards 4 and 5. Having its extremity 6 hingedly secured, as shown, to the upper extremity of the standard 4, the opposite extremity 7 thereof being in detachable connection with the upper 60 extremity of the standard 5, is a substantially horizontally disposed stepped bar 8 substantially coextensive in length with the member 1. Such connection between the bar 8 and the standard 5 is preferably effected 65 by providing the extremity of the former with a pair of projecting studs 9 adapted to engage perforations 10 formed in the upper end of the latter. By forming said standard of a suitable resilient metal it is evident, 70 that the engagement of said studs with said perforations or the disengagement thereof therefrom, may be readily and quickly effected by simply springing said standard slightly outwardly. The bar 8 as shown, 75 and as above stated, is of step form, it being so designed in order to adapt the same to accommodate spools of various heights.

In use, upon releasing the end 7 of the bar 8 and swinging the latter upwardly 80 and outwardly, thread-spools of various sizes may be arranged upon any or all of the bearing pins 2 in the manner shown in dotted lines in Fig. 1. Upon returning said bar to normal or horizontal position and 85 securing the same in such position in the manner before described, said spools will be locked against displacement from the pins 2, but will be free to rotate thereon so as to permit of the ready uncoiling of thread 90 therefrom. A plurality of slits 11 is preferably provided in one edge of the base member whereby the free ends of the threads carried upon the spools arranged in the device, may be secured so as to prevent un- 95 raveling or uncoiling of the threads from the spools.

While I have shown what I deem to be the preferable form of my device I do not wish to be limited thereto as there might be 100 various changes made in the details of construction and the arrangement of parts without departing from the spirit of the invention comprehended within the scope of the appended claim. And although I have designed my device for the special purpose of holding thread-spools it may be used for 105 any other purpose to which it is applicable.

Having described my invention what I claim as new and desire to secure by Letters Patent is:

A spool holder comprising a base member; a plurality of pins of graduated lengths extending upwardly from said base member; flexible standards at the ends of said base member, one of said standards being provided with one or more perforations near 10 its top; and a stepped bar hinged to the

other standard and provided with one or more end projections adapted to enter said perforations, substantially as described.

In testimony whereof I have signed my name to this specification in the presence 15 of two subscribing witnesses.

SARA P. WILLIAMSON.
